US0D1037756S

(12) **United States Design Patent** (10) Patent No.: **US D1,037,756 S**
(45) Date of Patent: ** Aug. 6, 2024

(54) **COOKING APPLIANCE**

(71) Applicant: **LG Electronics Inc.**, Seoul (KR)

(72) Inventors: **Jaehung Chun**, Seoul (KR); **Taeoh Kim**, Seoul (KR); **Jonghak Lee**, Seoul (KR); **Junghoon Lee**, Seoul (KR)

(73) Assignee: **LG ELECTRONICS INC.**, Seoul (KR)

(**) Term: **15 Years**

(21) Appl. No.: **35/519,003**

(22) Filed: **Nov. 17, 2022**

(80) **Hague Agreement Data**

Int. Filing Date: **Nov. 17, 2022**

Int. Reg. No.: **DM/225256**

Int. Reg. Date: **Nov. 17, 2022**

Int. Reg. Pub. Date: **Nov. 17, 2023**

(30) **Foreign Application Priority Data**

May 17, 2022 (KR) 30-2022-0019548

(51) LOC (14) Cl. **07-02**

(52) U.S. Cl.

USPC **D7/355**; D7/323; D7/358; D7/403
